ECCENTRIC RUNNING TOY VEHICLE

Raymond Lohr and Ellsworth Baxter, Erie, Pa.,
assignors to Louis Marx & Company, Inc., New
York, N. Y., a corporation of New York

Application January 21, 1937, Serial No. 121,426

27 Claims. (Cl. 46—211)

This invention relates to toys, and more particularly to a vehicle toy arranged to run on any of a plurality of different complex paths.

The primary object of our invention is to generally improve vehicle toys. A more particular object resides in the provision of a vehicle toy which will steer itself in any one of a variety of courses, these courses being predetermined in nature, but being so numerous and so varied and in some cases so intricate, that the operation of the toy is amusing and entertaining over an indefinite period of time, instead of quickly becoming monotonous, as is the case with most vehicle toys.

Another and more detailed object of our invention is to so arrange a vehicle toy that it may be made to run in a straight line or to describe a circle of large, medium or small radius, the latter circles being smaller than what could be expected to be obtained from the normal steering action of the front wheels. Still another object is to so arrange the toy that it will describe one or more paths made up of straight lines and sharp turns. The arc turned by the vehicle depends, as will later appear, upon the structural parameters of the parts of the toy, and may be varied by manual control. In a typical case the sharp curve may turn the vehicle through an angle of either 90 degrees or 180 degrees. In the latter case, the vehicle will travel on a straight line, then turn back upon itself to approximately the starting position, whereupon it will again turn and retrace the original path. In the former case, that is, with ninety-degree turns, the vehicle will travel over a figure which is generally square with rounded corners.

Still another object is to devise mechanism whereby the vehicle may be run over one or more paths made up of curved lines and sharp turns; specifically, with the turns of 180 degrees and 90 degrees previously referred to, and with a suitable curvature for the normal travel of the toy between turns, the toy may be made to trace a triangle with curved sides or an octagon with curved sides.

In accordance with still another feature and object of our invention, the toy may be caused at long intervals to perform an unexpected sharp turn of long duration (causing the toy to turn through 360 degrees or more, for example). Inasmuch as this extra and unexpected turn may be produced occasionally as the toy is describing any of the paths above referred to, such as a square or ellipse with straight sides, or a triangle or octagon with curved sides, the over-all per-

formance is both puzzling and highly amusing.

In accordance with still another object of the invention, the toy is provided with appropriate reverse gear mechanism whereby it may be caused to run either forwardly or backwardly. Many of the intricate formations through which the toy may be made to travel seem even more erratic, unexpected and entertaining when the toy is traveling backward. By appropriate combinations of the various movements above referred to, the toy is readily put through any one of twenty-four different courses of travel, and this number may be readily increased still further by the provision of more than two angles or steering positions for the wheels, as will appear from the appended more detailed description of the toy.

Still another object of our invention is to obtain all of the foregoing movements while using simple and dependable mechanism which may be manufactured inexpensively for sale under quantity production conditions at a low price, and while housing all of the mechanism within a vehicle body which is itself attractively streamlined in simulation of a modern motor car.

To the accomplishment of the foregoing and other objects which will hereinafter appear, our invention consists in the vehicle toy elements and their relation one to the other, as hereinafter are more particularly described in the specification and sought to be defined in the claims. The specification is accompanied by drawings, in which:

Fig. 1 is a side elevation showing a toy embodying features of our invention while operating in normal running condition;

Fig. 2 shows the toy in position for executing a relatively sharp turn;

Fig. 3 is an inverted plan view of the toy;

Fig. 4 is a plan view of the chassis of the toy with the simulated vehicle body removed to expose the internal mechanism;

Fig. 5 is a fragmentary plan view similar to Fig. 4, but showing the mechanism in position for both short and long interval turns;

Fig. 6 is a side elevation taken in the plane of the line 6—6 of Fig. 4;

Fig. 7 is a section taken in elevation through the chassis on the plane of the line 7—7 of Fig. 4;

Fig. 8 is a section taken in the plane of the line 8—8 of Fig. 4;

Fig. 9 is a fragmentary elevation similar to Fig. 7, but showing the relation of the parts when the cross wheel or turning wheel is depressed; and

Figs. 10 through 21 are schematic diagrams ex-

55

planetary of a variety of paths which the toy may be caused to follow.

Referring to the drawings, and more particularly to Figs. 1 through 9, the toy comprises a vehicle body **B** normally running upon front wheels **F** and rear wheels **R**. The vehicle is propelled by a suitable motor such as the spring motor **M**, which is preferably geared to one only of the rear wheels **R** in order to assist turning of the toy. 10 The toy is further provided with a cross wheel **W** preferably located intermediate the front and rear wheels, this cross wheel being vertically movable in order to bring the same into or out of contact with the running surface, as is respectively indicated by Figs. 2 and 1 of the drawings. 15 The movement of cross wheel **W** may be obtained periodically in response to drive by the aforesaid motor **M**, and the character of movement obtained may be controlled by a suitable manually 20 movable control member **C**.

The vehicle may run on the front and rear wheels as shown in Fig. 1, and this may for convenience be referred to as the "normal" operation of the vehicle. When the cross wheel **W** is 25 depressed, the front wheels **F** are elevated slightly from the running surface, and the toy then runs on the cross wheel **W** and the rear wheels **R**, as shown in Fig. 2, and this may, for convenience, be referred to as the "turning" operation. It 30 should be understood, however, that the toy may travel on either a straight or a curved path during its "normal" operation, this being so because the front wheels may be fixed in any one of a plurality of angular or steering positions, as is 35 clearly indicated in Fig. 3 by the arrows **A** and **B** marked on the top. The angle through which the vehicle is turned when in the "turning" position of Fig. 2, may be varied by fixing the cross wheel **W** in one of a plurality of angles or 40 steering positions, indicated by the numerals **1** and **4** marked on the bottom of the toy, as is indicated in Fig. 3. By suitably positioning the control member **C**, the cross wheel **W** may be caused to remain elevated as in Fig. 1, or to remain lowered as in Fig. 2, or to be periodically 45 lowered at short intervals, or to be lowered at short intervals and additionally lowered for a longer time at longer intervals.

Considering the arrangement in greater detail the body of the toy is made up of a bottom or 50 chassis plate **12** and a top **14**. The radiator simulation **16** may be made of a separate piece of sheet metal. The parts **14** and **16** are secured together by appropriate tongue and slot connections and together form an upwardly convexed cover or 55 housing which is secured to the bottom **12** by a series of tongue and slot connections **18** extending entirely about the periphery of the bottom, as is best shown in Figs. 3 and 4. Inasmuch as the operating mechanism of the toy is mounted entirely upon the bottom or chassis member **12**, the 60 said mechanism is fully exposed when the upper parts **14** and **16** are removed, as shown in Figs. 4 through 9.

65 Referring now to these figures, the rear wheels **R** are mounted on an axle **20**. Only one wheel, in this case the wheel **22**, is secured to axle **20**, the other wheel **24** being freely rotatable on the axle. It will be noted that wheel **22** is the outside 70 wheel when the toy is turning on cross wheel **W** (this construction helps insure relatively sharp turning of the vehicle).

75 The motor **M** is here illustrated as a spring motor comprising a main spring **26**, the outer end of which is secured to the motor frame **28** at the

point **30**, and the inner end of which is secured to a main stem or winding stem **32**. Stem **32** is preferably connected to axle **20** through an appropriate train of step-up gearing. In the present case, stem **32** carries a gear **34** meshing with a pinion **36** mounted on an intermediate shaft **38** and turning with a gear **40** which in turn meshes with a pinion **42** (Fig. 7) mounted directly on rear axle **20**. The motor is wound by means of a conventional key having a square hole dimensioned to fit the end of stem **32**, the latter being exposed by a hole **44** in body **14**, as is best shown in Figs. 1 and 2. In order to permit winding of the motor without rotation of the wheels, a suitable ratchet may be disposed between the 10 motor and the wheels, and in the present case pinion **36** has a hub which passes freely through gear **40** and which on the opposite side of gear **40** carries ratchet wheel **46**. This ratchet wheel cooperates with a dog **48** pivotally mounted on 15 gear **40**. The parts are so faced that the ratchet turns freely past the dog when the motor is being wound, but carries the dog and gear **40** with it when the motor is unwinding.

In order to limit the speed of the vehicle, the 20 motor may be provided with suitable governor mechanism, and in the present case this employs a special train of step-up gearing, the gear **40** meshing with a pinion **50** which in turn drives a gear **52** meshing with a pinion **54**, which in turn 25 drives a gear **56** meshing with a pinion **58** mounted on the governor shaft **60**. Shaft **60** carries an eccentrically disposed weight **62** which functions to limit the unwinding speed of the 30 motor. The operation of the toy may be controlled by a stop lever **64**, the lower end of which is pivotally mounted on the motor frame, as 35 shown at **66** in Fig. 7, and the intermediate part of which may be moved toward or away from the eccentric weight **62**, as will be clear from inspection of Figs. 4 and 7. The upper end of lever **64** projects through a suitable slot in the top of the vehicle body, as is clearly shown in Figs. 1 and 2. With lever **64** in the position shown in Fig. 2, the motor is freed for operation, whereas with lever **64** in the position shown in Fig. 1, the 40 motor is locked. The eccentric weight **62** functions not only as a governor, but also as part of the stop mechanism of the toy.

The front wheels **F** are mounted on an axle 45 **68** journaled in flanges **70** and **72** turned upwardly from bottom plate **12**. Flange **70** has a hole receiving axle **68**, as will be clear from inspection of Fig. 7, while flange **72** is provided with an elongated slot **74** best shown in Fig. 6. Slot **74** is enlarged at its ends to form detents **76** and **78** (see Fig. 6), and axle **68** is normally pressed upwardly by a leaf spring **80**, one end of which is secured to plate **12** at **82**, and the other end **84** of which bears upwardly against carrier **86**, the forward end of which receives axle **68**. The purpose of carrier **86** will be described subsequently, but for the present it may be observed that the carrier is flanged upwardly at its side edges **88** and **90** and that flange **88** is apertured 55 to receive axle **68**, as is best shown in Fig. 7, while flange **90** is slotted at **92** to receive axle **68**, as is best shown in Fig. 6. Because of slot **92**, there is no interference with steering oscillation of the front axle as between the positions shown 60 in solid and broken lines in Fig. 3. Specifically, in the present case the detent **76** is so located that axle **68** is maintained at right angles to the longitudinal axis of the vehicle; hence in the 65 position shown in Fig. 4, the toy runs on a straight 70 75 75

line. When, however, the axle is moved until received in detent 78 (see Fig. 6), the front wheels are shifted to the position shown in broken lines in Fig. 3, and the toy follows a curved path. The 5 wheels are readily shifted between the positions designated A and B in Fig. 3, by seizing and moving the same manually.

The cross wheel or turning wheel W is mounted on an axle 94, one end of which may, if desired, 10 be prolonged to form a handle 96. The axle is carried in the side walls 98 and 100 of a suitable U-shaped support 102, the top or closed end of which is secured to carrier 86, as by the use of tongue and slot connections 104. Wall 98 is provided with a hole receiving one end of axle 94, 15 while wall 100 is provided with an elongated slot 106 best shown in Fig. 8. The ends of slot 106 are enlarged to form detents 108 and 110, and axle 94 is normally urged upwardly by the lower 20 end 112 of a wire spring the upper end 114 of which is secured on wall 100. With this arrangement the angular position of the cross wheel W is readily changed from that corresponding to the center line 116 of Fig. 3 to center line 118 in 25 Fig. 3. In the present case this is indicated on the toy itself by the numerals 1 and 4, the handle 96 being movable to either of the numerals. With the handle 96 at numeral 4, the wheel W causes the toy to turn on the smallest available 30 radius, while with the handle 96 at numeral 1, the vehicle turns on a somewhat larger radius, though the radius is still small compared to what would be obtainable from the steering action of the front wheels F alone.

The cross wheel W may be periodically lowered by mechanism driven from the spring motor M. Referring to Figs. 4 and 7, it will be seen that intermediate shaft 38 carries a cam 120, the said cam being secured to gear 40 by arm 122. The carrier 86 heretofore referred to is vertically 40 oscillatable by reason of its pivotal mounting on front axle 68. It is normally elevated, as shown in Fig. 7, by means of a leaf spring 124, the forward end of which is secured to chassis 12 at 126 and the rear end of which bears upwardly against 45 the bottom of carrier 86. With the parts in the position shown in Figs. 4 and 7, the rear end 128 of carrier 86 is disposed beneath cam 120 and acts as a cam follower. During each revolution 50 of intermediate shaft 38 the carrier 86 is depressed by cam 120 and the cross wheel W is thus brought into contact with the running surface. The duration of the contact of cross wheel W with 55 the running surface depends upon the speed of intermediate shaft 38 and the peripheral length of cam 120.

These factors may be designed with considerable latitude. In the present case, the design is such that the toy is caused to turn 180 degrees, 60 that is, it performs a U-turn when the cross wheel W is in shortest radius turning position, that is, the position 4 in Fig. 3. At the same time, the difference in angle between the positions 1 and 4 of the cross wheel is such that in position 1 the vehicle turns 90 degrees. It will be appreciated that because of a number of factors, such as slippage of the driving wheel 22 on the running surface, the angle turned by the toy depends somewhat upon the nature and smoothness 65 of the running surface, and also varies slightly depending upon whether the toy is freshly wound or nearly unwound. In the present toy the turning wheel W is rubber-tired, while the front and rear wheels for the sake of economy are 70 made of sheet metal. The performance of the 75

toy depends upon this factor as well, it being modified somewhat if the wheels are all rubber-tired.

We have so far described the first mechanism whereby the cross wheel may be periodically depressed. The present toy is additionally provided with a second mechanism which periodically depresses the cross wheel, but preferably at substantially longer intervals and for a somewhat longer time. Specifically, the main driving gear 34 is 10 provided with a camming pin 130 adapted to bear against an arm 132 the lower end of which is pivoted on the motor frame at 134 and the upper end of which is turned inwardly at 136 to dispose the same above the adjacent edge 138 of carrier 86, as is best shown in Fig. 5. Arm 132 may be held against sideward movement by a disc 140 mounted on stem 32, the camming pin 130 extending between gear 34 and disc 140, and the arm 132 being disposed therebetween. If desired, arm 132 may normally be held in elevated position by a wire spring 142. It will be evident from a comparison of Figs. 7 and 9, that upon rotation of gear 34 the camming pin 130 bears 20 downwardly against arm 132, the end 136 of which 25 in turn depresses carrier 86 against the influence of leaf spring 124, and thus lowers the cross wheel into contact with the running surface. This operation takes place regardless of the 30 position of cam 120. Inasmuch as there is a very 35 large step-up gear ratio between the winding stem 32 and the intermediate shaft 38, the interval between the functioning of cam 130 is very much longer than the interval of the functioning of cam 120. The duration of the lowering of the 40 cross wheel depends upon the radius of camming element 130 together with the relative disposition of the other parts of the mechanism, and we 45 preferably so arrange these parts that the cross wheel remains in contact with the running surface for a time substantially greater than that provided under the influence of cam 120. Specifically, we prefer to design the toy so that it turns 360 degrees or more whenever the camming element 130 is functioning.

The mode of operation of the cross wheel may be selected by use of the control member C previously mentioned. Referring now to Figs. 3 and 4, it will be seen that the control member C comprises a piece of sheet metal 144 pivotally 50 mounted at 146 on chassis 12, the said control member being oscillatable by means of a handle 148 projecting outwardly from the side of the vehicle. Member 144 is so shaped as to provide a surface 150 of small radius, a surface 152 of 55 intermediate radius, and a surface 154 of large radius, as well as a motion limiting stop 156. These surfaces are adapted to bear against the adjacent edge of wall 100 on which the cross wheel W is mounted. The entire carrier 86 is 60 bodily oscillatable about a vertical axis, as is indicated for example by the difference between the solid line position 86 in Fig. 4 and the broken line position 86'. This movement is readily obtained by reason of the mounting heretofore described, for carrier 86 receives axle 68 by means of a hole in flange 88, whereas it receives axle 68 by means of a slot in flange 90. The carrier is therefore bodily oscillatable about axle 68 at the flange 88. The carrier is normally urged counter-clockwise as viewed in Fig. 4, or clockwise as viewed in Fig. 3, in order to hold the same against control member C, by means of a pull spring 158 tensioned between the hook 160 formed on the chassis 12 and a hook 162 formed on carrier 86. 70 75

With the control member C in the position shown in Figs. 3 and 4, that is, with the surface 152 of intermediate radius in use, the cam follower end 128 of carrier 86 is disposed beneath cam 120, but the edge 138 of carrier 86 is not disposed beneath the inturned lug 136 of arm 132. In this position the cam 120 functions, but the cam element 130 is rendered inoperative. When the control element is turned to bring the large radius surface 154 against the cross wheel mount, the carrier is moved to the broken line position shown in Fig. 4, at which time the cam follower end 128 is moved out of the path of cam 120 and the latter is made inoperative. When, however, the control element C is moved in opposite direction to bring the smallest radius surface 150 into use, the carrier 86 is moved counterclockwise relative to the position shown in Fig. 4, thus bringing the same to the position shown in Fig. 5, at which time the edge 138 comes beneath inturned lug 136 and both camming mechanisms 120 and 130 are made operative.

The three positions of control member C are indicated on the toy, as by the numerals 1, 2 and 3 shown in Fig. 3, the said numerals being used in cooperation with a suitable arrow or pointer on the control member.

The control member C may be used for still another function, namely to hold the cross wheel W permanently in lowered position. Referring to Fig. 8, it will be seen that the side wall 100 is notched near its upper end at 164. If the cross wheel is drawn down from the elevated position shown in solid lines to the lowered position shown in broken lines, the notch 164 reaches the control member C and by swinging the control member to the large radius position, that is, to the numeral 3, the edge of the control member is moved into recess 164 and thus locks the cross wheel in lowered position. At this time the cross wheel is preferably lowered somewhat more than the amount which it is lowered by the camming mechanisms 120 and 130, thus avoiding any possibility of recess 164 reaching the control member during the periodical depressions of the cross wheel under motor drive. The cross wheel may be locked in depressed position only by manually moving the same to fully lowered position. With the cross wheel locked in depressed position, it may, of course, be moved to either of the angular or steering positions, thus causing the toy to describe either a small or medium sized circle, both of these circles, however, being substantially smaller than what may be obtained by use of the steering action of the front wheels.

In order to increase the number of actions obtainable from the toy, and because some of the more intricate movements of the toy are even more surprising and amusing when performed with the toy running backwardly, we prefer to equip the toy with reversing mechanism. Referring to Figs. 4 and 7, it will be seen that the rear axle 20 is carried in ears 166 turned upwardly at the outer extremities of a T-shaped member 168, the stem 170 of which projects outwardly through the bottom of the toy at the rear end thereof. The manner in which the control arm 170 extends out of the toy will be clear from inspection of Figs. 1, 2 and 3 of the drawings. Fig. 7 shows the manner in which the upwardly curved bottom wall 172 is slotted at 174 to receive the arm 170. The side edges of arm 170 are turned downwardly or flanged at 176, and these flanges are notched to form spaced detent recesses 178 and 180 which cooperate with a detent lug 182.

A leaf spring 184 secured to the bottom of the toy at 186 bears downwardly and normally holds one or the other of the recesses on detent 182.

The ends of the T-shaped plate beneath the ears 166 rest directly on the marginal or higher level parts of the bottom 188 (Figs. 3 and 7).

The motor frame carries an idle pinion 190 so disposed that when the reverse arm 170 is moved from the forward position shown in Fig. 7 to a rearward position in which notch 178 is disposed on detent 182, the axle pinion 42 is disengaged from gear 40 and engages pinion 190, which in turn is constantly in mesh with gear 40. The direction of rotation of axle 20 is thus reversed. To shift from forward to reverse or vice versa, it is merely necessary to preliminarily lift the arm 170, thus freeing the detent, and to thereupon slide the arm forwardly or rearwardly, the forward position corresponding to forward drive of the vehicle, and the rearward position corresponding to rearward drive of the vehicle.

It is believed that the construction and operation of our improved toy vehicle, as well as the many advantages thereof, will be apparent from the foregoing detailed description. By way of review, however, the operation may be described with reference to the schematic diagrams shown in Figs. 10 through 21 of the drawings. If the front wheels F are disposed in position A in Fig. 3, and if the control member C is moved to position 3, thus making both camming mechanisms inoperative, the toy simply runs on a straight line, as shown in Fig. 21. If now the front wheels are changed from the straight line position A to the angular steering position B, the toy describes a circle of large radius, as shown in Fig. 14. In a practical case, this diameter may, for example, be 48 inches.

If the cross wheel W is turned downwardly and locked in depressed position by control member C (the control member being in position 3 and the steering position of the front wheels being immaterial), the toy will be caused to turn on a circle of small radius. If at this time the cross wheel is in position 4 in Fig. 3, the toy will describe a small circle as shown in Fig. 15, and if the cross wheel is moved to position 1 of Fig. 3, the toy will describe a somewhat larger circle, as shown in Fig. 16. In a practical case these circles are 22 inches and 32 inches in diameter, respectively.

If the front wheels are left straight, that is, in position A, and if the control member C is moved to position 2, thus making the cam 120 operative, the toy will describe a figure made up of straight lines and sharp turns. With the cross wheel in position 4, the toy will run back and forth repeatedly, this figure being indicated by Fig. 10. The length of the straight run relative to the length of the sharp turn may be greater than is shown in Fig. 10. This figure may, for want of a better term, be referred to as an ellipse. If the cross wheel W is moved from position 4 to position 1, so that the turn is 90 degrees rather than 180 degrees, the toy will describe a figure such as that indicated in Fig. 11, this figure being substantially a square with rounded corners.

If the front wheels are changed from position A to position B, the "normal" running of the toy will be on a curve rather than a straight line. This curve we prefer to make in a direction opposite to that produced by a cross wheel. The figure described by the toy is then made up of a series of curves, some of long radius and some of short radius. For example, with the cross wheel 75

in position 4 so that the toy turns 180 degrees, the toy will describe a triangle with curved sides, substantially as indicated in Fig. 12. If, however, the cross wheel is moved to position 1 so 5 that the toy turns approximately 90 degrees, the vehicle will describe a polygon with curved sides, substantially the octagonal figure shown in Fig. 13.

If the control member C is moved to the position 1, thereby making both camming mechanisms 120 and 130 effective, each of Figs. 10, 11, 10 12 and 13 will be reproduced with the additional surprise element of an unexpected sharp turn by the vehicle at relatively long intervals. This is 15 schematically indicated by Figs. 17 through 20. In Fig. 17, for example, the ellipse has superposed thereon a complete circle of movement it being understood that in practice the toy runs back and forth about the ellipse a number of times 20 before the unexpected circling of the toy takes place. It will also be understood that inasmuch as the circling of the toy may be more than 360 degrees, the vehicle may thereafter describe an ellipse in a different direction than that previously maintained. To produce this figure, the front wheels are put in position A, the cross wheel is put in position 4, and the control member is put in position 1.

Similarly, in Fig. 18 the toy describes a straight-sided polygon with rounded corners, and at relatively long intervals the operation is interrupted by an unexpected turning movement of the toy. This figure is obtained with the parts as previously described, but with the cross wheel changed 35 from position 4 to position 1.

Figs. 19 and 20 will be understood from the foregoing remarks, without additional detailed comment, it being understood that in all cases the figures have been somewhat idealized for convenience and that the axis of each of the figures may be changed by the long interval turning movement. To produce Fig. 19, the front wheels are changed from position A to position B, and the cross wheel is placed in position 4; while to 45 produce Fig. 20, the cross wheel is placed in position 1.

In this way 12 different courses may be described by the toy, and by appropriate use of the reverse mechanism the number of operations may be increased to 24. The variety in operation is still further increased by reason of the difference in traction on various running surfaces, such as a rough cement floor, a polished floor, etc., and also because in practical operation the toy occasionally encounters a wall or other obstacle, and is thus deflected from its course. Because of the numerous variables involved, the operation in a practical case is not readily discoverable to be a specific geometric figure, and the paths such as 50 Figs. 13 and 20 apparently simulate the erratic course of an automobile operated by a novice or an intoxicated driver. The zig-zag turning movements of the toy are highly amusing to watch, and the amusement is enhanced when 55 the toy is operated in reverse.

It will be apparent that while we have shown and described our invention in a preferred form, many changes and modifications may be made in the structure disclosed without departing from the spirit of the invention defined in the following 60 claims.

We claim:

1. A toy vehicle comprising front wheels, rear wheels, a driving motor geared to a rear wheel in 65 order to propel the vehicle, a cross wheel inter-

mediate the front and rear wheels, mechanism for periodically raising and lowering the cross wheel in order to bring the same into and out of contact with the running surface, and additional mechanism for depressing the cross wheel at longer intervals, said mechanism being driven by the aforesaid motor. 5

2. A toy vehicle comprising front wheels, rear 10 wheels, a driving motor geared to a rear wheel in order to propel the vehicle, a cross wheel intermediate the front and rear wheels, mechanism for periodically raising and lowering the cross wheel in order to bring the same into and out of contact with the running surface, said mechanism being driven by the aforesaid motor, and means 15 whereby the cross wheel may be locked in depressed position.

3. A toy vehicle comprising front wheels, rear 20 wheels, a driving motor geared to a rear wheel in order to propel the vehicle, a cross wheel intermediate the front and rear wheels, mechanism for periodically raising and lowering the cross wheel in order to bring the same into and out of contact with the running surface, said mechanism being driven by the aforesaid motor, a control 25 member for making the mechanism operative or inoperative at will, and means whereby the cross wheel may be locked in depressed position.

4. A toy vehicle comprising front wheels, rear 30 wheels, a driving motor geared to one of said rear wheels in order to propel the vehicle, a cross wheel intermediate the front and rear wheels and ahead of the center of gravity of the toy, a cam and cam follower mechanism for periodically raising and lowering the cross wheel in order to bring the same into and out of contact with the running surface, whereby said vehicle runs on either the rear wheels and front wheels, or on the rear wheels and the cross wheel, said cam being driven by the aforesaid motor, said cam 40 follower being movable either into or out of cooperation with the cam, and a control member for moving the cam follower into or out of cooperation with said camming means. 35

5. A toy vehicle comprising front wheels, means 45 whereby the front wheels may be fixed or locked in one of a plurality of steering positions, rear wheels, a driving motor geared to one of the rear wheels in order to propel the vehicle, a cross wheel intermediate the front and rear wheels and ahead of the center of gravity of the toy, and mechanism for periodically raising and lowering the cross wheel in order to bring the same into and out of contact with the running surface, said mechanism being driven by the aforesaid motor, whereby said vehicle runs on either the rear 50 wheels and front wheels or on the rear wheels and cross wheel. 55

6. A toy vehicle comprising front wheels, means 60 whereby the front wheels may be fixed in one of a plurality of steering positions, rear wheels, a driving motor geared to one of said rear wheels in order to propel the vehicle, a cross wheel intermediate the front and rear wheels, mechanism for periodically raising and lowering the cross wheel 65 in order to bring the same into and out of contact with the running surface, and additional mechanism for depressing the cross wheel at longer intervals, said mechanism being driven by the aforesaid motor. 70

7. A toy vehicle comprising front wheels, means 75 whereby the front wheels may be fixed in one of a plurality of steering positions, rear wheels, a driving motor geared to a rear wheel in order to propel the vehicle, a cross wheel intermediate

- the front and rear wheels, mechanism for periodically raising and lowering the cross wheel in order to bring the same into and out of contact with the running surface, said mechanism being driven by the aforesaid motor, and means whereby the cross wheel may be locked in depressed position.
8. A toy vehicle comprising front wheels, means whereby the front wheels may be fixed in one of a plurality of steering positions, rear wheels, a driving motor geared to one of the rear wheels in order to propel the vehicle, a cross wheel intermediate the front and rear wheels and ahead of the center of gravity of the toy, mechanism for periodically raising and lowering the cross wheel in order to bring the same into and out of contact with the running surface, whereby said vehicle runs on either the rear wheels and front wheels, or on the rear wheels and cross wheel, said mechanism being driven by the aforesaid motor, and a control member for making said mechanism operative or inoperative.
9. A toy vehicle comprising front wheels, means whereby the front wheels may be fixed in one of a plurality of steering positions, rear wheels, a driving motor geared to a rear wheel in order to propel the vehicle, a cross wheel intermediate the front and rear wheels, mechanism for periodically raising and lowering the cross wheel in order to bring the same into and out of contact with the running surface, said mechanism being driven by the aforesaid motor, a control member for making said mechanism operative or inoperative, and means whereby the cross wheel may be locked in depressed position.
10. A toy vehicle comprising front wheels, rear wheels, a driving motor geared to a rear wheel in order to propel the vehicle, a cross wheel intermediate the front and rear wheels, means so mounting the cross wheel that it may be fixed in one of a plurality of angles or steering positions, and mechanism for periodically raising and lowering the cross wheel in order to bring the same into and out of contact with the running surface, said mechanism being driven by the aforesaid motor.
11. A toy vehicle comprising front wheels, rear wheels, a driving motor geared to a rear wheel in order to propel the vehicle, a cross wheel intermediate the front and rear wheels, means so mounting the cross wheel that it may be fixed in one of a plurality of angles or steering positions, mechanism for periodically raising and lowering the cross wheel in order to bring the same into and out of contact with the running surface, and additional mechanism for depressing the cross wheel at longer intervals, said mechanism being driven by the aforesaid motor.
12. A toy vehicle comprising front wheels, rear wheels, a driving motor geared to a rear wheel in order to propel the vehicle, a cross wheel intermediate the front and rear wheels, means so mounting the cross wheel that it may be fixed in one of a plurality of angles or steering positions, mechanism for periodically raising and lowering the cross wheel in order to bring the same into and out of contact with the running surface, said mechanism being driven by the aforesaid motor, and means whereby the cross wheel may be locked in depressed position.
13. A toy vehicle comprising front wheels, rear wheels, a driving motor geared to a rear wheel in order to propel the vehicle, a cross wheel intermediate the front and rear wheels, means so mounting the cross wheel that it may be fixed in

one of a plurality of angles or steering positions, mechanism for periodically raising and lowering the cross wheel in order to bring the same into and out of contact with the running surface, said mechanism being driven by the aforesaid motor, and control means for making said mechanism operative or inoperative.

14. A toy vehicle comprising front wheels, rear wheels, a driving motor geared to a rear wheel in order to propel the vehicle, a cross wheel intermediate the front and rear wheels, means so mounting the cross wheel that it may be fixed in one of a plurality of angles or steering positions, mechanism for periodically raising and lowering the cross wheel in order to bring the same into and out of contact with the running surface, said mechanism being driven by the aforesaid motor, control means for making said mechanism operative or inoperative, and means whereby the cross wheel may be locked in depressed position.

15. A toy vehicle comprising front wheels, means whereby the front wheels may be fixed in one of a plurality of steering positions, rear wheels, a driving motor geared to a rear wheel in order to propel the vehicle, a cross wheel intermediate the front and rear wheels, means so mounting the cross wheel that it may be fixed in one of a plurality of angles or steering positions, and mechanism for periodically raising and lowering the cross wheel in order to bring the same into and out of contact with the running surface, said mechanism being driven by the aforesaid motor.

16. A toy vehicle comprising front wheels, means whereby the front wheels may be fixed in one of a plurality of steering positions, rear wheels, a driving motor geared to a rear wheel in order to propel the vehicle, an idle cross wheel intermediate the front and rear wheels, means so mounting the cross wheel that it may be fixed in one of a plurality of angles or steering positions, a cam and cam follower mechanism for periodically raising and lowering the cross wheel in order to bring the same into and out of contact with the running surface, said cam being driven by the aforesaid motor, said cam follower being movable either into or out of cooperation with the cam, and a control member for moving the cam follower into or out of cooperation with said cam.

17. A toy vehicle comprising front wheels, means whereby the front wheels may be fixed in one of a plurality of steering positions, rear wheels, a driving motor geared to a rear wheel in order to propel the vehicle, an idle cross wheel intermediate the front and rear wheels, means so mounting the cross wheel that it may be fixed in one of a plurality of angles or steering positions, a cam and cam follower mechanism for periodically raising and lowering the cross wheel in order to bring the same into and out of contact with the running surface, said cam being driven by the aforesaid motor, and said cam follower being movable either into or out of cooperation with the cam, control means for moving the cam follower into or out of cooperation with said cam, and means whereby the cross wheel may be locked in depressed position.

18. A toy vehicle comprising rear wheels, a driving motor geared to a rear wheel in order to propel said vehicle, front wheels, a cross wheel intermediate the rear and front wheels, said cross wheel being vertically movable in order to bring the same into or out of contact with the running surface, resilient means normally

elevating the cross wheel, and a control member for locking the cross wheel in depressed position.

19. A toy vehicle comprising rear wheels, a driving motor geared to a rear wheel in order to propel said vehicle, front wheels, means whereby the front wheels may be fixed in one of a plurality of steering positions, a cross wheel intermediate the rear and front wheels, said cross wheel being vertically movable in order to bring the same into or out of contact with the running surface, resilient means normally elevating the cross wheel, and a control member for locking the cross wheel in depressed position.

15 20. A toy vehicle comprising rear wheels, a driving motor geared to a rear wheel in order to propel said vehicle, front wheels, a cross wheel intermediate the rear and front wheels, said cross wheel being vertically movable in order to bring the same into or out of contact with the running surface, resilient means normally elevating the cross wheel, a control member for locking the cross wheel in depressed position, and means whereby the cross wheel may be fixed 25 in one of a plurality of angular steering positions.

21. A toy vehicle comprising rear wheels, a driving motor connected to one of said rear wheels, front wheels, a cross wheel intermediate the rear and front wheels, carrier means to 30 lower or raise the cross wheel in order to bring the same into or out of contact with the running surface, cam means driven by said spring motor at a predetermined frequency for actuating said carrier means, control means whereby 35 the cam means may be made operative or inoperative to actuate the carrier, and means to vary the angle through which the vehicle is turned upon each depression of the cross wheel by the cam means.

40 22. A toy vehicle comprising rear wheels, a driving motor connected to one of said rear wheels, front wheels, a cross wheel intermediate the rear and front wheels, carrier means to lower or raise the cross wheel in order to bring 45 the same into or out of contact with the running surface, whereby said vehicle runs on either the rear wheels and front wheels, or on the rear wheels and cross wheel, cam means driven by said motor at one predetermined rotational frequency for actuating said carrier means, cam 50 means driven by the said motor at another predetermined rotational frequency for actuating said carrier means, control means whereby neither cam means or the first cam means alone 55 or both the first and second cam means may be made operative to actuate the carrier.

23. A toy vehicle comprising rear wheels, a driving motor connected to one of said rear wheels, front wheels, a cross wheel intermediate 60 the rear and front wheels, carrier means to lower or raise the cross wheel in order to bring the same into or out of contact with the running surface, cam means driven by said motor at one predetermined frequency for actuating said carrier means, cam means driven by said motor at another predetermined frequency for actuating 65 said carrier means, control means whereby neither cam means or the first cam means alone or both the first and second cam means may be 70 made operative to actuate the carrier, and means to vary the angle through which the vehicle is

turned upon each depression of the cross wheel by the cam means.

24. A toy vehicle comprising front wheels, rear wheels, a driving motor geared to one of said rear wheels in order to propel the vehicle, a cross 5 wheel intermediate the front and rear wheels, a cam and cam follower mechanism for periodically raising and lowering the cross wheel in order to bring the same into and out of contact with the running surface, said cam being driven by the 10 aforesaid motor, and said cam follower being movable either into or out of cooperation with the cam, additional camming means for depressing the cross wheel at longer intervals, and control means for moving the cam follower into or 15 out of cooperation with either or both of said camming means.

25. A toy vehicle comprising front wheels, rear wheels, a driving motor geared to one of said rear wheels in order to propel the vehicle, a cross 20 wheel intermediate the front and rear wheels, a cam and cam follower mechanism for periodically raising and lowering the cross wheel in order to bring the same into and out of contact with the running surface, said cam being driven by the 25 aforesaid motor, and said cam follower being movable either into or out of cooperation with the cam, additional camming means for depressing the cross wheel at longer intervals, control 30 means for moving the cam follower into or out of cooperation with either or both of said camming means, and means whereby the cross wheel may be locked in depressed position.

26. A toy vehicle comprising front wheels, rear 35 wheels, a driving motor geared to one of said rear wheels in order to propel the vehicle, an idle cross wheel intermediate the front and rear wheels, means so mounting the cross wheel that it may be fixed in one of a plurality of angles or steering 40 positions, a cam and cam follower mechanism for periodically raising and lowering the cross wheel in order to bring the same into and out of contact with the running surface, said cam being driven by the aforesaid motor, and said cam follower being movable either into or out of cooperation 45 with the cam, additional camming means for depressing the cross wheel at longer intervals, and control means for moving the cam follower into or out of cooperation with either or both of said camming means.

50 27. A toy vehicle comprising front wheels, rear wheels, a driving motor geared to one of said rear wheels in order to propel the vehicle, an idle cross wheel intermediate the front and rear wheels, means so mounting the cross wheel that it may be fixed in one of a plurality of angles or steering 55 positions, a cam and cam follower mechanism for periodically raising and lowering the cross wheel in order to bring the same into and out of contact with the running surface, said cam being driven by the aforesaid motor, and said cam follower being movable either into or out of cooperation with the cam, additional camming means for depressing the cross wheel at longer intervals, control 60 means for moving the cam follower into or out of cooperation with either or both of said camming means, and means whereby the cross wheel may be locked in depressed position.
